UNITED STATES PATENT OFFICE.

JOHN VAN BRUNT, OF NEW YORK, N. Y., ASSIGNEE TO COMBUSTION ENGINEERING CORPORATION, OF NEW YORK, N. Y., A CORPORATION OF NEW YORK.

FURNACE.

1,423,281.

Specification of Letters Patent. Patented July 18, 1922.

Application filed June 22, 1918. Serial No. 241,333.

To all whom it may concern:

Be it known that I, JOHN VAN BRUNT, a citizen of the United States, residing at the city, county, and State of New York, have invented a certain new and useful Improvement in Furnaces, of which the following is a full, clear, and exact description.

My invention relates to improvements in furnaces and has for its object to provide a stoker furnace having a new and improved system for supplying air for combustion purposes. It further has for its object to provide means for supplying air to selected fuel areas or zones and controlling the supply of air to such zones. It further has for its object to provide means for cutting off the supply of air from various fuel areas or zones. It further has for its object to secure proper combustion of carbon in the burning out zones upon the dumping grates.

The following is a description of an embodiment of my invention, reference being had to the accompanying drawings, in which,—

Fig. 1 shows a transverse section, on the line I—I of Fig. 2, of a portion of a furnace embodying my invention;

Fig. 2 is a view partially in plan and partially in section on the line II—II Fig. 1, and

Fig. 3 is an enlarged detail.

Referring more particularly to the drawings, 1—1 are the vertical walls of a retort. 2—2 are series of tubular fire or grate bars supported upon the walls 1—1 at their inner ends, by which I mean ends adjacent to the retort, and at their outer ends upon the upper edges of the walls of primary or main air boxes 3—3. These tubular grate bars are provided with tuyère openings 4—4 discharging adjacent to the retort into the ignition and coking zone. Alternate grate bars are provided with lugs 5—5, which are engaged by projections upon rocker bars 6, which are oscillated in any suitable manner, as, for instance, the manner shown in patent to W. R. Wood, No. 818,010 dated Apr. 17, 1906, so that the alternate bars are reciprocated as the rocker bars are oscillated while the intermediate bars remain stationary. 7—7 are air supplying ducts connected with the air boxes 3, said air boxes 3 being connected with the passages through the tubu-

lar grate bars 2 so that air being supplied under pressure through the ducts 7 may pass through the grate bars so as to be heated and then wholly or partly discharged through the tuyère openings 4. From this it results that air discharged through the tuyère openings 4 to the freshly supplied coal in the ignition and coking zones 8 is heated so as to hasten the ignition and coking of the fuel in that zone. 9—9 are auxiliary or secondary air boxes separated from each other by a partition 10 so as to be independent of one another. In the walls 11 separating the primary air boxes 3 from the secondary air boxes 9 are openings which may be opened and closed by sliding dampers 12 actuated by the rods 12' so that the two adjacent boxes 3 and 9 may be placed in communication with one another to a greater or less extent, or separated from one another as desired. Hugging the rocker bars 6 are baffles 13, having depending walls 14 forming, with the walls 1 of the retort, channels which may be opened and closed by the swinging dampers 15, each controlled by a handle 15'.

When the dampers 15 are open, as shown at the left of Fig. 1, air from the ducts 7 passes through the box 3 and grate bars 2 and is partly discharged through the tuyère openings 4 to the ignition and coking zone 8 and partly discharged downwardly into the box 9 from whence it rises upwardly between the grate bars of the corresponding series to the combustion zone 8'. When the damper 15 is closed, as shown at the right hand side of Fig. 1, the air which passes through the grate bars is substantially all discharged through the tuyère openings 4 to the zone 8. As the conditions of the fuel in the combustion zone 8' upon the body of the grate bars demand, the dampers 12 may be opened and closed so as to allow more or less air to pass directly from the main air boxes 3 to the secondary air boxes 9, and thus pass up between the grate bars without passing through the passages in the same. Thus the dampers 12 and 15 may both simultaneously be closed so that substantially all the air supplied is discharged through the tuyère openings 4, or the damper 12 may be closed with the damper 15 open so that all the air supplied passes through the grate bars, part of it being discharged through the tuyère openings and part of it passing

between the grate bars after passing through the same; or the dampers 15 and 12 may both be opened more or less so that part of the air which passes between the grate bars 5 shall have traversed the grate bars while part passes directly to the compartment 9 beneath the grate bars through ports controlled by the damper 12. Or the damper 15 may be closed and the damper 12 open 10 so that substantially all the air which passes upward between the grate bars is supplied directly through the damper 12.

16 are the ordinary dump grates located beneath the outer ends of the grate bars. It 15 sometimes happens that unconsumed carbon reaches the burning out zone 8² above these dump grates and in order that air may be supplied thereto for its proper combustion, I provide the walls 17 of the primary 20 air boxes 3 with sliding dampers 18 controlled by handles 19 so that air may be admitted from the primary air boxes 3 to the ash pits 20 below the dump grates and, passing upward through the matter supported thereby, aid in the complete combustion 25 of any carbon contained therein.

On account of unavoidable air leakage 30 between the abutting surfaces upon the outer ends of the grate bars and the support for their outer ends when the grate bars contain air under pressure, any unconsumed coke which reaches the dump grates 16, adjacent to the point of discharge of such leakage, is liable to become so highly incandescent as to injure the portions of the grate 35 bars and dump grates adjacent thereto if such air is allowed to impinge directly upon such coke. In order to prevent such direct impingement in the construction shown, I 40 place on the lower side of the outer extremities of the grate bars lips 21, which extend into the path of the leaking air, breaking up the jets of air and causing it to diffuse and pass through the openings between the 45 grate bars and the dump grates at a low velocity, thus reducing the intensity of the resulting combustion.

Air is supplied to the ducts 7 from a conduit 22, the supply to those ducts being controlled by valves 23, the conduit and these valves being shown in dots in Fig. 2.

From the foregoing it will be seen that there are three separate and distinct pressure compartments from which the air may pass 50 through the fuel adjacent to each series of grate bars. These compartments are respectively the tubular compartments or hollow grate bars, from which the tuyères 4 lead, the auxiliary compartments 9 and the 55 ash pits 20 beneath the dump grates 16, and connections to or from all these compartments are subject to manual control by the dampers 15, 12 and 18, so that the pressures in those separate compartments may be 60 varied more or less independently. It is also 65

to be noted that the pressure in the compartments on the two sides of the stoker may be varied independently, the two sides being separated by the wall 10.

With the arrangement shown, the air in 70 passing from the main air box 3 to the tuyères 4 absorbs the heat from the grate bars, keeping the grate bars relatively cool. The air discharged from the tuyère is heated air. When operating at high ratings or 75 with certain kinds of coal this preliminary heating before discharging into the igniting and coking zone 8 is a decided advantage as it improves the ignition particularly with low grade or low volatile fuels or with 80 coals running high in moisture. With this arrangement also the pressure in the compartments 9, 9, beneath the grate bars can be increased and diminished so as to be independent of the amount of heated air passing 85 through the grate bars, the thickness of the fire above the grates and the space between the grates, thus enabling a sufficient pressure to be maintained beneath the grate bars in order to obtain satisfactory combustion 90 in the combustion zone 8'. In case sufficient air does not pass through the tuyères 4 the damper 15 can be closed more or less and the damper 12 regulated so that the pressure at the tuyères 4 can be increased 95 to whatever extent is desirable, producing the proper relation between the pressures at the tuyères and in the chamber 9 to get satisfactory ignition and coking and combustion 100 conditions.

Since by reason of the separation of the two halves of the system by the wall 10, it is possible to control the air to the zones on either side of the retort independently of the other, the air can be adjusted on either 105 side so as to increase the combustion rate on the side where the fire is heavier and bring the fire on that side down to the same thickness as on the other side.

When running at extremely low ratings 110 or with thin fires, the air pressure in the auxiliary boxes 9 may be reduced or shut off entirely and substantially the entire combustion carried on in the zone 8.

Since the dampers 18 make it possible to 115 admit air directly under the dump grates it is possible to burn out any unconsumed carbon which may remain, assuring that nothing but non-combustible will be dumped into the ash pit. By varying the initial air 120 pressure by means of the dampers 23, located in the passages leading from the passage 22 to the ducts 7, it is possible to obtain a great variety of draught and pressure variations 125 in the various compartments to meet a great variety of conditions of fire thickness and fuel that may arise in the several zones 8, 8', 8², 8², and to compensate for different conditions of the fuel body when changing from one fuel to another. 130

In embodying my invention I prefer to use a retort having a series of grate bars extending from each side as shown, but as will be evident to those skilled in the art, my invention permits of various modifications without departing from the spirit thereof or the scope of the appended claims.

What I claim is:

1. In a stoker furnace, the combination of 10 a retort, a series of grate bars extending therefrom and having air passages between them, said grate bars being tubular and having on their lower faces ports at both ends, a duct for supplying air to the ports 15 at the ends remote from said retort so as to pass through said bars and discharge from the ports adjacent to said retort, means comprising a damper adjacent to said retort ends for controlling the discharge of 20 air through said last named ports, and a chamber located below the central portion of said bars into which the air from said last mentioned ports discharges when said damper is open, said bars having tuyère 25 openings at their retort ends through which some of the air entering at their other ends discharges.
2. In a stoker furnace, the combination of 30 a retort, a series of grate bars extending therefrom and having air passages between them, said grate bars being tubular and having on their lower faces ports at both ends, a duct for supplying air to the ports at the ends remote from said retort, so as 35 to pass through said bars and discharge from the ports adjacent to said retort, means comprising a damper adjacent to said retort ends for controlling the discharge of air through said last named ports, and a 40 chamber located below the central portion of said bars into which the air from said last mentioned ports discharges when said damper is open, said bars having tuyère 45 openings at their retort ends through which some of the air entering at their other ends discharges, and means for connecting and disconnecting said duct and chamber so as to permit air to pass directly from said duct to said chamber when desired.
3. In a stoker furnace, the combination of 50 a retort, a series of grate bars provided with air passages between them and extending from said retort, said grate bars being tubular and being provided with ports in 55 the lower faces of both ends thereof, a passage for supplying air to said bars so as to enter the ports at their ends remote from said retort and pass through said bars and discharge from the ports adjacent to said 60 retort, means comprising a damper located adjacent to the retort ends of said bars for controlling the passage of the air through the ports adjacent to the retort, a chamber located below the central portions of said bars 65 into which chamber air passing through
- 70 said bars discharges when said damper is open, said bars having tuyère openings at their retort ends through which some of the air entering at their other ends discharges, dump grates at the ends of said bars remote from said retort, an ash chamber below said dump grates, and means for connecting and disconnecting said passage with either or both of said chambers when desired.
4. In a stoker furnace, the combination 75 of a retort, two series of tubular grate bars extending from opposite sides thereof, the bars of each series having air passages between them, said bars being provided at both ends with ports on their lower faces, 80 ducts for supplying air to the ports at the ends remote from said retort so as to pass through said bars and discharge through the ports at the ends adjacent to said retort, means comprising dampers located adjacent 85 to said retort for controlling the discharge of air from the ports adjacent to said retort, said bars having tuyère openings adjacent to said retort, and chambers located beneath the central portions of said 90 two series of bars respectively into which bars of the respective series discharge air when said dampers are open, said chambers being separated from one another.
5. In a stoker furnace a combination of a 95 retort, a series of tubular grate bars extending therefrom, said bars having tuyère openings at their retort ends, a chamber located below the central portions of said bars, and a duct adapted to supply air directly both to the 100 ends of said tubular bars remote from said retort and to said chamber, so that air from said duct may pass directly to and through said bars and discharge through said tuyère 105 openings and air from said duct may pass directly to said chamber and escape therefrom between said bars, said bars having air passages between them.
6. In a stoker furnace a combination of 110 a retort, a series of tubular grate bars extending therefrom, said bars having tuyère openings at their retort ends, a chamber located below the central portions of said bars, and a duct supplying air directly both to the ends of said tubular bars remote from 115 said retort and to said chamber, so that air from said duct passes directly to and through said bars and discharges through said tuyère openings and air from said duct passes directly to said chamber and escapes 120 therefrom between said bars, said bars having air passages between them, and a damper located between said duct and said chamber for controlling the passage of air to said chamber.
7. In a furnace, the combination of a 125 retort, a series of tubular grate bars having air passages between them, said grate bars being provided on their lower sides and adjacent to their respective ends with ports 130

and having their inner ends supported adjacent to said retort, a primary air box connected to the ports at corresponding ends of said tubular grate bars to supply air thereto, a secondary air box receiving air from the ports at the other ends of said tubular grate bars, and dump grates extending from the outer ends of said tubular grate bars, said outer ends being engaged and supported by a portion of one of said air boxes, the engaging surfaces of said portion and of said bars being located between the dump grates and the ports adjacent to said outer ends, said outer ends having depending projections situated outside of said portion and extending below the supporting surface thereof so as to deflect downwardly air leaking between said portion and the lower surfaces of the outer ends of said bars engaged thereby and thus interfere with the free passage of such air directly to the material upon said dump grates.

8. In a stoker furnace a combination of a retort, a series of tubular grate bars extending therefrom, said bars having tuyère openings at their retort ends, and ports on their lower sides adjacent to both ends, a chamber located below the central portions of said bars, and a duct supplying air directly both to the ports in the ends of said tubular bars remote from said retort and to said chamber, so that air from said duct passes directly to and through said bars and discharges through said tuyère openings and air from said duct passes directly to said chamber and escapes therefrom between said bars, said duct and chamber con-

stituting air boxes, said grate bars having air passages between them, and dump grates extending beneath said remote ends of said tubular grate bars, said remote ends being engaged and supported by a portion of one of said air boxes, the engaging surfaces of said portion and of said bars being located between the dump grates and the ports adjacent to said outer ends, said outer ends having depending projections situated outside of said portion and extending below the supporting surface thereof so as to deflect downwardly air leaking between said portion and the lower surfaces of the outer ends of said bars engaged thereby and thus interfere with the free passage of such air directly to the material upon said dump grates.

9. In a stoker furnace, the combination of a retort, a series of grate bars extending therefrom and having air passages between them, said grate bars being tubular and having on their lower faces ports at their ends and having at their retort ends tuyère openings communicating with their interiors, a duct for supplying air to the ports at the ends remote from said retort so that it passes through said bars and discharges both from the ports adjacent to said retort and through said tuyère openings, a chamber located below the central portions of said bars and adapted to receive air from said last named ports, and means controlling the flow of air to said chamber comprising a damper located between said last named ports and said chamber.

JOHN VAN BRUNT.
